UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

SUBDIVIDED SERVICE SYSTEM OF RADIO BROADCAST DISTRIBUTION.

Application filed July 9, 1924. Serial No. 725,086.

My invention relates to systems of radio broadcast distribution of the type which I have designated by the name Radiowire, in which use is made of wired circuits, connecting subscribers' stations with a central station. It has for its object to simplify the subscriber's radiophone instruments, and at the same time to extend the scope or range thereof as well as the power. Other objects 10 are to unify and standardize the service rendered, to permit supervision and control by operators at the central station of all lines and substation receiving, to give the central office supervision and custody of 15 the more delicate, complicated and costly apparatus required in long distance radio reception, to reduce the amount of such complicated and costly apparatus, and to centralize all high voltage and high power current 20 supply apparatus. Other objects will sufficiently appear from the detailed description hereinafter.

I attain my objects as follows:

I locate at each subscriber's station a simple radio receiving set having a wave collector, and a carrier wave transformer by means of which the modulated carrier waves received may be transformed into modulated carrier waves of different wave lengths suitable for line-radio transmission to the central office. At the central office I locate units for receiving said line transmitted carrier waves, and for first amplifying the same at radio frequency, then detecting and 35 amplifying the modulations at audio frequency and then transmitting the amplified audio frequency waves back over the subscriber's line to his station where they are rendered audible by means of any suitable 40 telephone receiving instrument.

My invention is illustrated in the accompanying drawings, in which,

Fig. 1 is a diagram of a subscriber's station, and a line circuit leading therefrom 45 to a central station.

Fig. 2 is a diagram of cooperating circuits at the central station.

Figs. 3, 4 and 5 are diagrams of modifications of the apparatus at the central 50 station.

Referring to the drawings in detail, and first to Figs. 1 and 2, 1 and 2 represent a subscriber's telephone line extending from

the subscriber's station Fig. 1, to the central office Fig. 2 where it terminates in line terminal apparatus which may be of any known or other suitable form indicated symbolically by the cut-off jack J. At the subscriber's station, Fig. 1, is provided the usual telephone instrument T_e arranged to be connected to the line 1-2 through conductors 3-4 and switch S_w. A loud speaker L_s is also connected across the line 1-2 through switch S_{w'} and conductors 5-6. The subscriber's station is also provided with a radio receiver S of the beat or heterodyne type whose output terminals 7-8 are connected to the line wires 1-2. The input conductors 18-19 of the subscriber's radio receiver S are connected with the loop antenna L 70 which may be substituted by any suitable form of wave intercepting device. The subscriber's receiver S consists generally of that portion of the well known superheterodyne receiver comprising the first detector, oscillator, and intermediate frequency or filter coupler with a suitable current source. In this arrangement T' is the first detector tube having the grid g connected to one of the input terminals 19 through the grid condenser C² and grid leak g₁ and its filament f connected to the other input terminal 18 through the tapped coupler coil i of an oscillator coupler I. The plate p of the first detector is connected to the plus terminal of the "B" battery B through conductor 12, coil i² of the filter coupler I', and conductors 80 11 and 16, the plate return circuit being by way of the connection of the filament f through conductor 15 to the minus terminal 85 of the "B" battery. The oscillator tube T' has its grid g' connected through the coil i² of the oscillator coupled I to the filament f' while its plate element p' is connected 90 through coil i' of the oscillator coupler and conductor 16 to the plus terminal of the "B" battery, the plate return circuit being from the filament f' through conductor 15 to the minus terminal of the "B" battery. The plate and grid terminals of the coils i' and i² 95 are connected through an oscillator tuning condenser C³ while the other terminals of the coils i' and i² are connected through a fixed coupling condenser C⁴. The filaments f and f' are connected, as usual, through a suitable individual rheostats R_{h'} and R_h² 100 105

across the terminal of the "A" battery A by way of conductors 14 and 15. The primary coil i^3 of the filter coupler I' is bridged by a condenser C⁶ of the proper capacity 5 to form with the coil a tuned circuit resonant at the desired beat or intermediate frequency as is usual in the filter coupler of the well known superheterodyne circuit. The arrangement of the secondary or output 10 side of the filter coupler I' varies somewhat from the usual type in that the coil i^4 instead of being bridged by its tuning condenser C⁶ has this condenser connected in series therewith and with the line so as to make the 15 line part of the resonant filter circuit, the condenser C⁶ being of the variable type to afford sharp tuning.

At the central office, the connection of the line wires 1—2 is extended through the normally closed contacts of the cut-off jack J 20 to the conductors 21—20 which connect with the terminal conductors 23—24 of a filter coupler I² which forms the input coupling connection to the central office amplifier CO.

25 This filter coupler comprises coupling inductance i^5 and i^6 with their tuning condensers C⁷, and C⁸, respectively, arranged similarly to those of the filter coupler I' of the subscriber's receiver and having substantially the same electrical constants. The circuit of the central office amplifier CO from the filter coupler I² to the output jack J' is the intermediate frequency and audio frequency amplifier portion of the well known 8-tube 30 superheterodyne, so that the system as shown in Figs. 1 and 2 is in effect a split, 8-tube superheterodyne with the first detector and oscillator at the subscriber's station connected over the line to the remainder of the circuit at the central office. The central office amplifier CO therefore consists of the usual three stages of intermediate radio frequency amplification effected by the three amplifier tubes T³, T⁴, and T⁵, detection effected by the detector tube T⁶, and two 35 stages of audio amplification effected by the amplifier tubes T⁷, and T⁸, which several tubes are connected through suitable radio transformers T_r¹, T_r², and T_r³, and audio transformers T_r⁴ and T_r⁵. The usual source 40 of current at various potentials is provided in the form of a storage battery tapped to form a filament or "A" battery A', low voltage or conductor "B" battery B²², and high voltage or amplifier "B" battery B²⁰ 45 connected as usual in the filament circuits, second detector plate circuit and amplifier plate circuits, respectively. The voltage divider, or so-called potentiometer, P₀ is provided in the grid return circuits of the amplifier tubes T⁴ and T⁵ for the purpose of stabilizing the radio frequency stages, the filament return circuits being by-passed for radio frequency currents around the voltage 50 divider through conductor 28, by-pass con- denser C¹⁰ and conductor 25. The audio output jack J' is connected through a plug P₇ and conductors 41—42 to the line extension conductors 21—20, respectively for the purpose of putting the amplified audio output 55 from the amplifier back on the subscriber's line, the audio being blocked off from the input side of the amplifier by the low capacity condenser C⁷ which in the present instance is approximately .00025 mf. 60 As the plate voltage of the last amplifier tube T⁸, 90 volts, is much higher than that for which the ordinary telephone receiver is designed it is, of course, desirable to use 65 a step down transformer between the line and the ordinary telephone receiver at the subscriber's station where this receiver is to be used in place of the loud speaker L_s, although in practice it has been found that 70 very good reception can be had on the ordinary telephone receiver R even with the loud speaker connected across the line, reception of the loud speaker being nearly all cut-off due to the low resistance shown. It is also 75 to be noted that where desirable the loud speaker L_s may be designed to operate on a lower voltage substantially the same as that of the regular receiver R, and the voltage transformation effected at the central office. It is to be understood that suitable 80 switches may be inserted in any of the conductors such as the line extensions 21—20, input conductors 23—22, battery leads, etc. for the purpose of throwing the circuits in 85 and out of operative condition as is usual 90 and well known in the art.

In operation, the subscriber may use his regular telephone for initiating or receiving telephone calls over his telephone line 1—2 95 in the usual way through the telephone exchange system, not shown. When the subscriber at the substation Fig. 1 desires to receive radio broadcast he secures, through the aid of the central office operators and supervisors, a connection with his line 1—2 100 through extension 21—20 with the input and output terminals of a central office amplifier CO as indicated in Fig. 2, opens the switch S_w to disconnect his telephone set Te from the line and connects his loud speaker L_s to the line by closing the switch S_{w'} and adjusts the wave length condenser C' and heterodyne or oscillator condenser C⁸ in the usual manner of operation of the 105 well known superheterodyne set to produce with the desired wave a beat wave corresponding to the wave length to which the filter couplers I' and I², and the line 1—2 are tuned. The long or intermediate frequency wave is thus transmitted over the 110 line 1—2 through the coupler I² to the input side of the intermediate frequency and audio frequency amplifier CO at the central station, from which amplified audio output 115 currents are conducted over the extension 120 125 130

pair 41-42, line extension 21-20, normally closed contacts of cut-off jack J, subscriber's line 1-2 to the subscriber's loud speaker L³ by way of cord conductors 5-6. As all the 5 adjustments of the amplifier CO are fixed, the subscriber has control of his reception by the condensers C' and C³ and by suitable adjustments of such condensers may select any station within the radius of 10 reception, the extent of which range will be substantially the same as that of an 8-tube superheterodyne set located wholly at the subscriber's station. It will thus be seen that the subscriber's apparatus is reduced to a very 15 simple form having but two tubes and no transformers, high potential batteries, or other of the more delicate and costly elements of the superheterodyne circuit, these latter elements being provided at the central office where they may be readily repaired or replaced by experts with little or no interruption to the subscriber's service. It is contemplated to provide interchangeable amplifier units CO at the central office 20 which will thus render the subscriber's reception substantially proof against interruption as it has been found in practice that the weakest portion of a circuit of this type is the amplifier circuit. It has also been 25 found in practice that the detector and oscillator tubes at the subscriber's station may be of a different type than those at the central office and designed to work at a lower filament and plate voltage. For example, 30 successful operation was had with two tubes of the UV-199 type with but sixteen volts on the plate circuits of both tubes.

The manner of connecting the audio output of the central office amplifier to the line 40 through a transformer is shown in Fig. 3 where I³ indicates the audio transformer having its primary winding i⁷ connected to the audio output conductor 41-42 and its secondary winding i⁸ connected to the line 45 extensions 21-20. Otherwise the central office apparatus of Fig. 3 is the same as that of Fig. 2 and may be used in substitution thereof with the subscriber's line circuit and substation apparatus of Fig. 1. The arrangement of Fig. 3 has the advantage of 50 rendering the amplifier more stable in its action as well as affording regulation of the mean voltage of the audio currents to that most suitable for transmission over telephone lines regardless of the voltage of the output currents of the amplifier which latter, in the present state of the art, usually requires relatively high voltages. To prevent 55 leakage of direct current over the line extensions 21-20 through the secondary i⁸ of the transformer, an audio condenser having a capacity of the order of 2 mf. may be connected in series with said winding.

The modified central office circuit of Fig. 60 4 may be substituted for that of Fig. 2 and

is the same as it except that the subscriber's line extension has but a single wire connection with the input of the amplifier. This connection is made with the extension conductor 20 through the conductor 43 to the 70 closed primary circuit of the filter coupler I². In actual use, this circuit is found to give very clear reception with reliable stability in the action of the amplifier.

In Fig. 5 is shown a further modification 75 of the central office amplifier connection which may be substituted for that of Fig. 2 and which was found in actual tests to give very good reception at the subscriber's loud speaker both as to clarity and volume. In 80 this arrangement the circuits are the same as that of Fig. 2 except that there is no physical coupling between the subscriber's line and the filter coupler I², the terminals of the primary circuit of the filter coupler 85 being connected with a twisted pair of insulated conductors. In the operation of this circuit it was found that reception was substantially unaffected by shortcircuiting the 90 twisted pair 30-31 at either end.

As the purpose of the subscriber's radio receiver of Fig. 1 is to receive broadcast on the available wave lengths and to convert it into suitable form to be transmitted to the central office with the original modulations for amplification and detection, without interference with the audio currents sent back to the subscriber, various other forms of receiving circuits capable of subserving this purpose may be used in substitution 100 thereof with the various central office amplifying circuits disclosed, for example, one tube may be saved in the subscriber's receiver by delegating the functions of oscillator and detector to one tube by the use 105 of the second harmonic as shown and described on page 59 of the booklet entitled "The Superheterodyne Manual" by Victor Grieff, published by "The Receptrad Press," 57 Bank Street, New York city, copyrighted 110 by Victor Grieff, 1924; the two tubes may be so connected that the first tube will act as a short wave radio amplifier and the second one as a second harmonic oscillator and detector, while by reflexing the first tube will 115 also act as an intermediate frequency amplifier which circuit arrangement is shown and described on page 60 of the publication just referred to; the subscriber's receiver may consist of a long wave oscillator modulated by the incoming broadcast signal, or the broadcast may be of the double modulated type and the subscriber's circuit comprise a detector for detecting an intermediate 120 carrier of sufficiently low frequency to be 125 transmitted over the subscriber's line to the central office. Another system which will enable the subscriber to receive broadcast matter on short wave lengths and convert the same into wave lengths suitable for efficient 130

amplification at a distant point would be one similar to that disclosed in my copending application Serial No. 691,821, filed February 9, 1924, in which, along with the broadcast matter, the subscriber is furnished with a second wave, also by pure radio, and of a frequency to produce with the first wave a beat wave of the desired frequency. While in the disclosure referred to, no detector is shown at the subscriber's station, it is to be understood that a detector may be used there to effect the detection or filtering out of the beat wave for transmission over the line with the original modulations thereon, the line being tuned to the beat frequency to act as the filter circuit of a superheterodyne system.

While I have herein illustrated and described certain specific embodiments of my invention for the purpose of disclosure, it is to be understood that the invention is not limited to such specific embodiments but contemplates all such modifications and variants thereof as fairly fall within the scope of the appended claims.

For example, the audio amplification or a portion of the amplification may be accomplished at the subscriber's station; all or portions of the transmissions may be effected over a single conductor or a plurality of conductors used either in common or specialized, and various coupling arrangements may be used between the output and input of the centralized amplifier circuit for regulating the input energy such as various inductive, capacity, or resistance coupling means preferably capable of variation so as to effect a maximum of amplification without producing over regeneration or throwing the system into independent oscillation.

In its broadest aspect the principle involved in this invention is that of collecting and transmitting waves at suitable frequencies from a subscriber's station to a central station, there to be amplified and transmitted back to affect responsive apparatus and thereby produce audible sounds. In addition to the specific arrangement herein disclosed, it is pointed out that when properly tuned the line may be regarded as a resonant circuit for any suitable frequency, or if provided with filters may be regarded as a suitable medium for the transmissions of certain bands of frequencies whereby modulated waves received at one station may be transmitted over the wires to another station, may be amplified at said second station, and may be retransmitted to the first station at any suitable frequency within the transmission range of the line. For example, by using the proper so-called super-regenerative arrangement to prevent injurious self oscillation, the same frequency may be transmitted both ways, as for ex-

ample the beat frequency produced by heterodyning. In such case, it will of course be necessary to provide a second detector at the subscriber's station, or so arrange the circuits of the first detector that the waves amplified and reflected back from the central station may be rectified and the audio modulations removed therefrom. Where the same frequency is employed, as above stated, the line being tuned thereto, would constitute a resonant circuit excited at the first or subscriber's station and with the resonance amplified and deriving additional energy or power from a source in the same circuit at the second or central station. Obviously then the oscillations would rise in the line until suitably checked, due to the principle of regeneration. Such checking or "chopping" means, which divide the train of waves being regenerated and amplified into groups or periods having a variation frequency above that of audition, are well known in the so-called super-regenerative system of Armstrong and need not be described herein in detail. It is also possible however to transform the frequency at the central office before sending back the modulated waves to the subscriber's station, either to audio as herein specifically described, or to any other higher carrier frequency, i. e. above the limit of audition, that may be within the line transmission range. In party line practice particularly, the application of the general principle claimed herein will involve the use of different carrier wave frequencies on the same line, in order to render it possible for different parties on that line to receive different modulated wave trains at the same time. It is to be understood therefore, that all transmission back or forth in or over a line, tuned or untuned, of modulated wave trains, for the purpose herein set forth, is within the scope of this invention, as set forth in the claims appended hereto. This would include the extreme case of reception and detection of modulated carrier waves at a subscriber's station, and the transmission therefrom to central over the line wires of audio waves, that is to say sound waves, to be amplified and sent back (in theory) over the line. As a matter of fact what would happen in such a case would be the absorption of energy through the amplifying means at the central station and the reimposition of the same current changes in phase, on the line, which in effect would be establishing a condition of negative resistance.

Having thus described my invention what I claim and desire to secure by Letters Patent is:

1. A radio receiving system comprising wave intercepting and transmitting means, amplifying means and signal receiving means, said wave intercepting means and

- receiving means being located at one point, and said amplifying means being located at a remote point with a conducting circuit connecting said intercepting means and 5 amplifying means tuned to the wave length of the current to be amplified and connections over the same circuit from said amplifying means to said receiving means, with means to differentiate the intercepted waves 10 as transmitted from the first point to the other or amplifying point, from the amplified waves at a different frequency retransmitted to the originating point for audio reception thereat.
- 15 2. A radio receiving system comprising a primary receiving station and a secondary receiving station, a conducting circuit connecting said stations, and means at the secondary station operating through opposite currents at different frequencies in said conducting circuit for amplifying signals received at the primary station, and retransmitting said amplified signals to the primary station.
- 20 3. A radio receiving system comprising a primary receiving station, and a secondary amplifying station, a conducting circuit connecting said stations, means for producing two non-interfering currents between said 25 stations guided over said conducting circuit, means at the receiving station for receiving and transmitting signals on one current to the secondary station, and means at the secondary station for amplifying and retransmitting said signals on the other current back to the primary station, with means 30 to render said amplified signals audible in the receiving apparatus of the receiving station.
- 35 4. A radio receiving system comprising a primary receiving station and a secondary receiving station, a conducting circuit connecting said stations, means at the primary station for transforming direct current into 40 a relatively low power carrier current, a source of current of relatively high power at the secondary station, means at the primary station for receiving signals and retransmitting the same on the low power carrier current to the secondary station, and means at 45 the secondary station for amplifying said signals by means of the high power source and retransmitting the same to the primary station, said transmission over said circuit 50 in opposite directions being on different frequencies.
- 55 5. A radio receiving system comprising a primary receiving station, and a secondary receiving station, a conducting circuit connecting said stations, means at the primary station for receiving and retransmitting signals over the conducting circuit to the secondary station, and means at the secondary station for amplifying and retransmitting said signals over the said conduct- 60 ing circuit to the primary station, said transmission over said circuit in opposite directions being on different frequencies.
6. A radio receiving system comprising a primary receiving station and a secondary receiving station, a conducting circuit connecting said stations, means at the primary station for receiving and retransmitting signals over the conducting circuit to the secondary station on alternating current of 70 a frequency at which the said conducting circuit is substantially resonant, a transformer-connected amplifying circuit at the secondary station having transformers substantially resonant to said alternating current and connected to receive and amplify said alternating current, means at the secondary station for detecting the signals from the amplified alternating current, and means for amplifying and transmitting said 75 signals by direct current over the conducting circuit to the primary station.
- 80 7. A radio receiving system comprising a primary receiving station and a secondary receiving station, a conducting circuit connecting said stations, means at the primary station for receiving and transmitting signals over said conducting circuit to the secondary station at relatively low power, and means at the secondary station for retransmitting 85 said signals over the conducting circuit to the primary station at relatively high power, said transmission over said circuit in opposite directions being on different frequencies.
8. A radio receiving system comprising a primary receiving station and a secondary receiving station, a conducting circuit connecting said stations, radio receiving apparatus at the primary station comprising the heterodyning and filter coupler portion of a 90 superheterodyne receiving set, having the secondary element of its filter coupler connected to the conducting circuit, amplifying apparatus at the secondary station comprising the intermediate frequency amplification 95 and audio amplification portion of a superheterodyne circuit having its input end connected to the conducting circuit through a filter coupler and its output circuit connected to the conducting circuit independently of 100 the said filter coupler, and telephone receiving means at the primary station connected to the conducting circuit.
- 105 9. A radio receiving system comprising in combination with a telephone exchange 110 system having a central office and subscribers' substations connected therewith over telephone lines, a subscriber's superheterodyne receiving set arranged with the receiving and heterodyning portion at the 115 subscriber's station and the amplifying portion at the central office, said portions being operatively connected through the subscriber's line, a filter coupler connected between said receiving and heterodyning por- 120 125 130

tion and the line, and means whereby long waves from said filter coupler will be transmitted over the line to the amplifier at the central office, means for retransmitting the amplified waves over the line to the subscriber's station, at a frequency different from that to which the filter coupler is

tuned, and receiving means at the subscriber's station adapted to reproduce said signals. 10

In testimony whereof I hereunto affix my signature.
